CLAIM

I claim the ornamental design for the elongated safety razor holder, as shown and described.

DESCRIPTION

FIG. 1 is a front view of an elongated safety razor holder showing my new design;

FIG. 2 is a rear elevation view thereof;

FIG. 3 is a top plan view thereof, the bottom plan view being a mirror image;

FIG. 4 is a right side elevational view thereof; and,

FIG. 5 is a left side elevational view thereof.

The broken lines connecting the outer solid lines along the head of the elongated safety razor holder represent the bounds of the claim. The remaining broken lines illustrate portions of the article. None of the broken lines form part of the claimed design.
